UNITED STATES PATENT OFFICE.

WILLIAM D. VINEY, OF SALTICK, OKLAHOMA.

AUTOMOBILE ENGINE-CRANKING APPARATUS.

Application filed April 22, 1927. Serial No. 185,719.

The present invention relates to an apparatus for cranking automobiles and like engines, and has for its prime object to provide a structure which is easy to manipulate for the purpose of cranking the engine so as to turn the crank shaft over a sufficient number of times to bring into firing operation all of the cylinders of the engine, thus making the starting of the engine more sure than with the ordinary hand crank now in common use.

A still further important object of the invention lies in the provision of a mechanism of this nature which is comparatively simple in its structure, in view of its advantages, is thoroughly simple, efficient and reliable in operation, not likely to easily become out of order and otherwise well adapted to the purpose for which it is designed.

With the above and numerous other objects in view as will appear as the description proceeds, the invention resides in certain novel features of construction and in the combination and arrangement of parts as will be hereinafter more fully described and claimed.

In the drawings:

Figure 1 is a front elevation of an automobile showing my improved cranking apparatus mounted thereon.

Figure 2 is a rear elevation of the mechanism.

Figure 3 is a longitudinal horizontal section taken substantially on the line 3—3 of Figure 2, looking downwardly.

Figure 4 is a perspective view of a rocker used in the apparatus.

Figure 5 is a detail view of the gearing, and

Figure 6 is a vertical transverse section taken substantially on the line 6—6 of Figure 2.

Referring to the drawing in detail, it will be seen that the numeral 5 denotes a bar which is adapted to be disposed across the front of the chassis of the automobile below the crank shaft thereof and to be held in place by straps 6 and 7 or in any other suitable manner. Standards 7' rise upwardly from the center of the bar 5 and have journaled therein a shaft 8 with a ratchet head 9 on one end to engage the usual ratchet head on the crank shaft of an engine. A gear 10 is fixed to the shaft 8 between the standards 7'.

A rod 11 is pivoted to the bar 5 as at 12. A lever 13 is pivoted to the rod 11 as at 14. A loop bracket 15 is secured, as at 16 to the bar 5 and the rod 11 extends therethrough and is limited in its swinging movement by the loop 15. A ratchet bar 17 is pivotally engaged at one end as at 18, to an intermediate portion of the lever 13. A rocker R has a solid intermediate portion 20 with an opening 21 extending therethrough. A frame 22 projects from one end of the intermediate portion 20 and spaced parallel arms 23 extend from the other end thereof and are connected adjacent the intermediate portion 20 by a pin 24. A pivot pin 25 is mounted in an intermediate portion of the vertically rising loop frame 26 attached to the bar 5 and this pin 25 extends through openings 28 in the intermediate portion of the arms 23. A rod 29 is pivoted, as at 30 and has a notch 31 to engage the end of the frame 22. A spring 32 is engaged with the rod 29 and the pin 24. A link 33 connects the lever 13 with the rod 29 and this link 33 extends through opening 21 and through a looped bracket 34 rising from the bar 5. In between the extremities of the arms 23 there is mounted a combined ratchet wheel and gear 35. The ratchet bar 17 is engaged with the ratchet of the combine structure 35 and the gear of this combine structure is meshable with the gear 10, when the rocker is rocked in a clockwise direction in Figure 2.

When the parts are disposed as shown in Figure 2, it will be seen that the lever 13 may be rocked to the left, causing the link 33 to swing the rod 29 to disengage the notch 21 from the frame 22 on the rocker R, and at the same time tension the spring 32 so as to cause the rocker to rock in a clockwise direction and mesh the gear of the combine structure 35 with the gear 10 and further movement of the lever 13 to the left will continue to tension the spring 32 and the ratchet bar 17 will slip over the ratchet portion of the combine structure 35.

When the lever 13 is swung to the right it will cause the rotation of the combine structure 35, thereby rotating the gear 10, shaft 8 and the crank shaft of the engine through the clutch or segment 9, so as to turn the engine over several times. When the engine has been started, the parts can be disposed as shown in Figure 2, since when the lever 13 is moved over to the position

shown in Figure 2, it will cause the rod 29 to engage the frame 22 of the rocker R and swing said rocker to disengage the gear of the combine structure 35 from the gear 10 and when the frame 22 is engaged with the notch 31, the parts will be held in this position.

It is thought that the construction, operation, utility, and advantages of this structure will now be quite apparent to those skilled in this art, without a more detailed description thereof.

The present embodiment of the invention has been disclosed in detail merely by way of example, since in actual practice it attains the features of advantage enumerated as desirable in the statement of the invention and the above description. It will be apparent that changes in the details of construction and in the combination and arrangement of parts may be resorted to, without departing from the spirit or scope of the invention as hereinafter claimed or sacrificing any of its advantages.

Having thus described my invention, what I claim as new is:

1. In a cranking apparatus of the class described, a bar adapted to be mounted transversely and horizontally at the front of an engine, a shaft, means for journaling the shaft on the bar, a gear on the shaft, a rocker, means for pivotally mounting the rocker intermediate its ends on the bar, a combined gear and ratchet wheel journaled on one end of the rocker, a lever, means for rockably mounting the lever on the bar, a ratchet bar on the lever engageable with the ratchet wheel of the combined ratchet wheel and gear, and spring means for normally swinging the rocker to mesh the gear of its combined ratchet wheel and gear structure with the first mentioned gear.

2. In a cranking apparatus of the class described, a bar adapted to be mounted

transversely and horizontally at the front 45 of an engine, a shaft, means for journaling the shaft on the bar, a gear on the shaft, a rocker, means for pivotally mounting the rocker intermediate its ends on the bar, a combined gear and ratchet wheel journaled 50 at one end of the rocker, a lever, means for rockably mounting the lever on the bar, a ratchet bar on the lever engageable with the ratchet wheel on the combined ratchet wheel and gear, and spring means for normally 55 swinging the rocker to mesh with the gear of its combined ratchet wheel and gear structure with the first mentioned gear, said means comprising an arm pivotally mounted on the bar, a link connecting the arm and the lever, and a spring connecting the arm and the rocker.

3. In a cranking apparatus of the class described, a bar adapted to be mounted transversely and horizontally at the front of 65 an engine, a shaft, means for journaling the shaft on the bar, a gear on the shaft, a rocker, means for pivotally mounting the rocker intermediate its ends on the bar, a combined gear and ratchet wheel journaled at one end 70 of the rocker, a lever, means for mounting the lever rockably on the bar, a ratchet bar on the lever engageable with the ratchet wheel on the combined ratchet wheel and gear, spring means for normally swinging 75 the rocker to mesh the gear of its combined ratchet wheel and gear structure with the first mentioned gear, said means comprising an arm pivotally mounted on the bar, a link connecting the arm and the lever, and a spring connecting the arm and the rocker, said rod being formed with a notch with 80 which one end of the rocker is engageable to hold said rocker in position with the gear of its combined gear and ratchet structure 85 out of mesh with the first mentioned gear.

In testimony whereof I affix my signature.

WILLIAM D. VINEY.
